CLAIM

The ornamental design for a base for meat chopper as shown and described.

DESCRIPTION

FIG. 1 is a front, left and top perspective view of a base for meat chopper, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, left and top perspective view of the base for meat chopper in a usable state.

The broken lines in the drawings depict portions of the base for meat chopper that form no part of the claimed design. The broken lines forming the meat chopper in FIG. 9 are for the purpose of illustrating environment and form no part of the claimed design.
